(57) **CLAIM**

The ornamental design for a U-clip component of a modular bracket system for connecting multiple shelves at variable angles, as shown and described.

DESCRIPTION

FIG. 1 is a perspective view of a U-clip component of a modular bracket system for connecting multiple shelves at variable angels.

FIG. 2 is a top view thereof.

FIG. 3 is a bottom view thereof.

FIG. 4 is a side view thereof.

FIG. 5 is a second side view thereof.

FIG. 6 is a front view thereof.

FIG. 7 is a rear view thereof.

FIG. 8 is a top plan view thereof shown in use;

FIG. 9 is a side plan view thereof shown in a second use; and,

FIG. 10 is a perspective view thereof shown in a third use. The broken lines shown represent portions of the modular bracket system that form no part of the claimed design.
